UNITED STATES PATENT OFFICE.

THOMAS J. TREICHEL, OF SAN FRANCISCO, CALIFORNIA.

AUTOMOBILE-CURTAIN WINDOW.

1,297,042.

Specification of Letters Patent. Patented Mar. 11, 1919.

Application filed November 27, 1917. Serial No. 204,256.

To all whom it may concern:

Be it known that I, THOMAS J. TREICHEL, a citizen of the United States, residing at the city and county of San Francisco and State of California, have invented new and useful Improvements in Automobile-Curtain Windows, of which the following is a specification.

This invention relates to a window, and particularly pertains to a window adapted to be formed through an opening in the fabric curtain of an automobile.

It has proven a matter of considerable difficulty to mount a window glass over an opening in the fabric curtain of an automobile, this being due to the excessive weight of the glass, the unusual vibration of the car and the difficulty encountered in securing the window frame to the flexible fabric curtain. This invention has therefore for its prime purpose the provision of a window frame which will positively engage and bind the marginal edges of the curtain fabric around the opening in a secure and slightly manner, and at the same time rigidly support the window glass. Another object of this invention is to provide a frame for the curtain window which will expose one of its members upon the outside of the curtain and will neatly cover and conceal a complementary frame member upon the curtain. It has a further object to provide a pair of complementary frame members so constructed that they may be easily brought into their aligned and assembled positions with relation to each other and the curtain and thus hold during the final clamping operation, thereby insuring that the frame may be accurately mounted in position and that the time consumed in assembling the frame may be greatly reduced when compared with the assembly time required in most other window curtains of common construction. Other objects will appear hereinafter.

The invention is illustrated by way of example in the accompanying drawings, in which—

Figure 1 is a view in elevation illustrating a fragmentary portion of a curtain with a window formed therethrough and encircled by the device with which the present invention is concerned.

Figs. 2 and 3 are perspective views illus-

trating the complementary frame members and their interlocking, centering and clamping elements.

Fig. 4 is a view in transverse section through the frame as seen on the line 4—4 of Fig. 1, disclosing the detail sectional formation of the frame members and the clamping action upon the fabric of the curtain and the glass.

Fig. 5 is a transverse section as seen on the line 5—5 of Fig. 1, disclosing the positive engaging means of the curtain by the frame.

Fig. 6 is a fragmentary view in perspective and section illustrating the manner in which the curtain fabric is secured to the frame members.

Referring more particularly to the drawings, 10 indicates a fabric curtain, which, in the present instance, is composed of an outer sheet of fabric 11 and an inner sheet 12. A window opening is formed through these sheets and may be of any desired configuration. Frame members 13 and 14 are provided to bind the marginal edges of the fabric at the opening and also to serve as a rigid mounting for a window glass 15.

The frame member 13 is preferably of polished or nickel-plated metal and is disposed on the outside of the curtain. As particularly shown in Fig. 4, a lip 16 is formed around the outer edge of this member and is adapted to lie in overlapping relation to the outer edge of the complementary frame member 14 for a purpose which will be hereinafter set forth. The inner edge of the frame member 13 is formed with a continuous recess 17 into which the outer edge of the window glass is adapted to seat. The flat face of this frame member is fitted with a series of fastening and centering studs 18 which extend perpendicularly therefrom and into openings 19 formed through the opposite frame member. These studs are threaded and receive countersunk clamping nuts 20 which act to bind the two frame members together and the fabric therebetween. Screws might be used, however, and the threads omitted from the studs.

The frame member 14 may be of metal or other material and is here shown as semi-circular in section, although it may be found convenient to use other sections. Extend-

ing from the flat face of this frame member are a series of pointed fastening pins 21 which are adapted to pass through the edges of the curtain fabric and into recesses 22 in the face of the frame member 13, thus securely engaging and locking the fabric in position.

In the application of this device to a window curtain the fabric sheet 11 is formed 10 with an opening having the same dimensions as the inside dimensions of the frame member 13. The sheet 12 is formed with an opening of somewhat smaller dimensions and the marginal edges of this opening are 15 slit radially at suitable intervals to each other to insure that when the fabric is carried around the frame member 14 it will conform neatly to the frame member and lie flat on the inner face thereof. Openings are 20 then formed through the fabric sheet 11 to admit the studs 18. The frame member 13 may then be placed in position around the opening in the sheet 11 with its studs through the small openings and the frame 25 member 14 placed in position with relation to the sheet 12 on the curtain, the curtain being brought around the member 14 and carried up to bring the pins 21 through certain of the tangs 23 formed by slitting the 30 edge of the opening. When this has been done the two frame members may be readily assembled by placing the studs 18 through the openings 19 and thereafter clamping them together by the nuts 20, thus simultaneously binding the edges of the fabric, 35 clamping the window glass 15 in place and drawing the lip 16 of the outer frame member 13 in overlapping relation to the frame member 14. This last operation will act to 40 seal the space between the two frame members and prevent the seepage of water down the fabric 11 and into the joint.

It will thus be seen that by the use of the 45 curtain window here disclosed a window opening may be readily closed in a manner to securely clamp the window glass in position, conceal the inner frame member, positively hold the marginal edges of the curtain

fabric in place and prevent a leakage of water through the frame.

Having thus described my invention, what I claim and desire to secure by Letters Patent is:

1. In combination with a curtain having a window opening, a sectional frame, said curtain having the edge portion thereof adjacent said opening engaged between the inner faces of the frame sections, means to secure the sections together, and a lip formed on the peripheral portion of the outer section and projecting outwardly beyond the inner face of said outer section and having its free edge engaged with the curtain so as to depress and form an angular part in the latter which angular part is of substantially 55 Z-shape and is engaged with the periphery of the inner section and seals the joint between the two sections.

2. In combination with a curtain having inner and outer fabric members with a window opening in each, a sectional frame, the inner fabric member extending over the outer face and inner edge and across the inner face of the inner section, and the outer fabric member being superimposed upon 75 that part of the inner fabric member which engages the inner face of the inner section, a window glass seated on said superimposed portions of the fabric members, the outer section being also seated upon said superimposed portions of the fabric members and having a cut-out on its inner circumference to receive the glass and having a marginal lip extending outwardly from the inner face thereof, said lip engaging the outer fabric 80 member and forming an angular part in the latter, which angular part embraces the periphery of the inner section.

In testimony whereof I have hereunto set my hand in the presence of two subscribing 85 witnesses.

THOMAS J. TREMCHEL.
